UNITED STATES PATENT OFFICE.

GEORGE A. TRACHTE AND ARTHUR F. TRACHTE, OF MADISON, WISCONSIN.

TROUGH.

Application filed May 14, 1920. Serial No. 381,321.

To all whom it may concern:

Be it known that we, GEORGE A. TRACHTE and ARTHUR F. TRACHTE, citizens of the United States, residing at Madison, in the 5 county of Dane, State of Wisconsin, have invented a new and useful Trough, of which the following is a specification.

The device forming the subject matter of this application is a trough, of the kind 10 used for feeding and watering animals, and for other purposes; and the invention aims to provide novel means whereby a water tight closure may be effected between the end member of the trough and the body portion 15 thereof.

It is within the province of the disclosure to improve generally and to enhance the utility of devices of that type to which the invention appertains.

20 With the above and other objects in view, which will appear as the description proceeds, the invention resides in the combination and arrangement of parts and in the details of construction hereinafter described 25 and claimed, it being understood that, within the scope of what is claimed, changes in the precise embodiment of the invention shown can be made without departing from the spirit of the invention.

30 In the accompanying drawings:—

Figure 1 shows in end elevation, a trough constructed in accordance with the invention; Figure 2 is a top plan showing one end of the trough; Figure 3 is a section taken on 35 the line 3—3 of Figure 1; and Figure 4 is a section taken on the line 4—4 of Figure 2.

The device forming the subject matter of this application preferably is made of metal and includes a frame 1 comprising a base 2, 40 upwardly and inwardly inclined sides 3 and top strips 4 disposed in a common plane and extended toward each other. The trough includes an end member 5 having a top flange 6 and provided with a flange 7 extended 45 around the remaining portion of the periphery, the end member 5 preferably being approximately semi-circular in form. A packing 8 rests against the flange 7. The flange 6 is provided with a hook-shaped 50 bead 9 receiving the forward or outer edge of the top strips 4 of the frame 1, for the double purpose of holding the strips against relative vertical movement, and for support-

ing the end member 5 on the frame 1. The flange 7 of the end member 5 is supplied 55 with a bead 10 into which the outer edge of the packing 8 fits. The body of the trough is shown at 11 and is bent upon itself to form outwardly extended flanges 12.

The body 11 of the trough rests adjacent 60 its longitudinal center on the base 2 of the frame 1, the end member 5 being received within the body, and the packing 8 being in contact with the body. The flanges 12 are located beneath the top strips 4, and are connected thereto by tightening devices 14 which may be bolts and nuts. Obviously, by tightening up the elements 14, the body 11 will be drawn against the packing 8 and a water tight joint at the end of the trough will be 70 afforded.

Having thus described the invention, what is claimed is:—

1. In a trough, a frame including a top; an end member having a flange provided 75 with a bead receiving the top, and having a second flange provided with a bead; a packing abutting against the second flange and received within the bead thereof; a body receiving the end member and engaged with the packing; and tightening means carried by the frame and engaging the body to hold the body against the packing.

2. In a trough, a frame comprising a base, 85 sides upstanding from the base, and top strips disposed in a common plane and extended toward each other from the sides, an end member provided with a top flange whereon the top strips rest, the flange being provided with a bead overhanging the top strips, the end member being provided with an outstanding second flange; a trough-shaped body cooperating with the second flange of the end member and provided with outstanding flanges spaced from the top strips; and tightening devices connecting the outstanding flanges of the body with the top strips.

In testimony that we claim the foregoing as our own, we have hereto affixed our signatures in the presence of two witnesses.

GEORGE A. TRACHTE.
ARTHUR F. TRACHTE.
